METHODS OF AND APPARATUS FOR MANUFACTURING THREAD OR THE LIKE

Fred J. Samerdyke, Rocky River, and Louis E. Lovett, Cleveland Heights, Ohio, assignors to Industrial Rayon Corporation, Cleveland, Ohio, a corporation of Delaware

Application December 11, 1935, Serial No. 53,918
Renewed August 4, 1939

19 Claims.

(Cl. 18—8)

This invention relates to the manufacture of thread, filaments, bands, tapes, ribbons, staple fibre or like articles, hereinafter referred to as "thread or the like," according to an evaporative method; more particularly, to the manufacture of such articles, regardless of their nature, according to a method in and by which the thread or the like is formed by extrusion of a suitable suspension, solution or other dispersion of a plastic mass in a fugitive liquid vehicle. Preferably such fugitive liquid vehicle comprises a volatile solvent which can be caused to evaporate and thus leave the thread or the like in a plastic or solid condition. The invention is especially useful in the manufacture according to the evaporative spinning process of artificial silk thread or the like, as, for example, the manufacture of such thread from suitable volatile solvent solutions of cellulose acetate, cellulose nitrate, cellulose ethers 10 or other cellulose derivatives.

Conventional machines for the manufacture of thread or the like according to the evaporative spinning process usually comprise a series of evaporative chambers in the upper portion of each of which are one or more spinning nozzles. A suspension, solution or other dispersion of a suitable plastic mass is extruded from the spinning nozzle, forming the thread or the like, which is drawn downward from the spinning nozzle and out of the chamber at the bottom thereof. The thread or the like is collected in any desired manner, usually with twisting, by appropriate devices located at the front of the machine. An evaporative medium is admitted to the chamber, preferably at the bottom, such evaporative medium usually being air, heated either externally or internally of the chamber, as by means of suitable pipes located therein. The fugitive liquid vehicle in which the plastic mass is suspended, dissolved or otherwise dispersed is caused to evaporate from the thread or the like during its passage through the evaporative chamber. Solvent-laden evaporative media are generally drawn off from the tops of the evaporative chambers and passed to suitable solvent recovery systems. The foregoing comments apply to most, if not actually all, commercially available evaporative spinning machines, but are particularly applicable to machines of the type employed for spinning thread or the like of cellulose acetate.

For the complete solidification of thread or the like of cellulose acetate, employing the solvents generally used and under the spinning conditions found most desirable, an exposure of approximately two seconds to warm air at temperatures

of 50 to 60° C. is required for thread or the like of ordinary denier. With spinning speeds of the order of 100 meters per minute, which, for economy and other reasons, are the most practicable, this necessitates a distance of from three to five yards, depending on the denier, between the spinneret and the point at which the thread or the like leaves the evaporative chamber. Even with this distance, an appreciable amount of the solvent remains in the thread or the like as it leaves the chamber and is lost. Conventional cellulose acetate spinning machines are therefore tall, usually at least twelve feet high, and the spinneret is consequently positioned at a considerable height above the operator; so that, even if the chamber wall at the operating face of the machine is provided with a window, it is impossible to observe the spinneret closely from the floor. The spinneret can be inspected only from a catwalk provided at the rear of the machine for maintenance purposes. The height of the evaporative chamber results in still other disadvantages, among them the height of the plant building required, difficulty in constructing the machine, difficulty in servicing and repairing the machine, and difficulties in maintaining proper temperatures and other spinning conditions. Analogous considerations apply to machines for the manufacture of thread or the like, regardless of its nature, by evaporative spinning processes other than the cellulose acetate process.

It is an object of this invention, among other things, to minimize difficulties arising from the height of the evaporative chamber heretofore required by reducing the height of such chamber while nevertheless providing complete solidification of the thread or the like. It is a further object of the invention to make possible an increase in the amount of the solvent recovered from thread or the like manufactured according to evaporative methods. It is still a further object of the invention to expose to the effects of the treating medium a greater length of thread or the like than heretofore possible. Other objects of the invention will in part be obvious and will in part be brought out more in detail in the appended description and claims.

Briefly, the invention involves, inter alia, the employment in association with an evaporative chamber of one or more thread-storage devices, preferably, but not necessarily, of a type on which a length of thread or the like is temporarily stored, continuously treated and positively advanced in the form of a relatively large number of helical or generally helical turns. One or more

thread-storage devices may be disposed within the evaporative chamber, in separate chambers associated therewith, or outside of the evaporative chamber. If desired, a plurality of thread-storage devices may be employed in various combinations of these arrangements. In all of these cases, advantages result which will be explained more in detail hereinafter.

For illustration, but in no sense of limitation, 10 the invention will be described in connection with the manufacture of multiple filament artificial silk thread produced from an acetone solution of cellulose acetate.

In the drawings, in which are depicted five different embodiments of the invention and in which like reference numerals refer to like parts throughout, Figure 1 is a sectional elevation from line 1—1 of Figure 2 of one embodiment of the invention in which a single thread-storage device is 15 employed in conjunction with a relatively short evaporative chamber; Figure 2 is a front elevation of the same embodiment with parts broken away for the sake of clearness. Figure 3 is a section along line 3—3 of Figure 4 of one form of thread-storage device which may be used to advantage in the practice of the invention; Figure 4 is an end elevation thereof; and Figure 5 is a section corresponding to that of Figure 3 of another form of thread-storage device, the same including means 20 for supplying treating medium to the thread or the like from the interior of the device. Figure 6 is a section along line 6—6 of Figure 7 showing another embodiment of the invention in which a plurality of thread-storage devices are disposed 25 in a relatively short evaporative chamber. Figure 7 is a front elevation of the embodiment of Figure 6 parts being shown as broken away.

Figure 8 is a sectional elevation along line 8—8 of Figure 9 of another embodiment of the invention 30 embracing a plurality of thread-storage devices associated with a relatively short evaporative chamber, means being provided for applying treating medium to the thread stored thereon. Figure 9 is a corresponding front elevation with 35 parts broken away. Figure 10 is an elevation along line 10—10 of Figure 11 of an embodiment of the invention including a relatively long evaporative chamber, a first thread-storage device disposed within said chamber, and a second thread- 40 storage device positioned outside said chamber. Figure 11 is a front elevation of the same embodiment, parts being broken away. Figure 12, which corresponds to line 12—12 of Figure 13, illustrates an embodiment of the invention employing 45 a plurality of thread-storage devices, in this case two, associated with a relatively long evaporative chamber on each of which devices treating medium may be applied to the thread; Figure 13 is a corresponding front elevation, parts being broken 50 away; and Figure 14 is an elevation along line 14—14 of Figure 12 showing a method of mounting the thread-storage devices.

In the embodiment of Figures 1 and 2, the multiple filament thread 1 is formed in the usual 55 manner by extrusion of the spinning solution of cellulose acetate, containing acetone as a solvent, from the spinneret 2 into the evaporative chamber 3. While more than one spinneret may be positioned in each evaporative chamber, only one 60 is shown here for the purpose of illustration. A plurality of evaporative chambers 3 may, as in conventional evaporative spinning machines, be disposed side by side in a longitudinal bank or series, as shown in all the illustrated embodiments 65 of the invention, in which case advantages as to

construction, power drives, etc., result. The walls of the evaporative chambers 3 may be suitably insulated, as in conventional practice, for temperature control. The spinning solution may be supplied to each spinneret in any desired manner as by means of supply line 4 and pump 5 which is driven through gears 6 from drive shaft 7, common to all spinneret pumps, and which communicates with the spinneret 2 through pipe 8 and candle filter 9.

10 The thread 1, after being formed by extrusion, passes to a suitable thread-storage device 11 on which any desired length of thread may be continuously but temporarily stored, for purposes to be later described, after which it may be collected 15 by any suitable device, as by cap-twister 12.

15 Thread-storage device 11 may take any suitable form. Preferably, a thread-storage device is used on which the thread is positively advanced in a large number of helical or generally helical turns. 20 The thread-storage devices illustrated in Figures 3, 4 and 5 take the form of reels of the same general type as that shown, described and claimed in an application entitled "Winding reel," Serial No. 652,089, filed January 16, 1933, in the name of 25 Walter F. Knebusch. If desired, reference may be had to the corresponding British patent, which is identified as specification No. 413,414.

25 The reel of Figures 3 and 4 comprises two rigid generally cylindrical members 13 and 14, rotatably mounted with their axes slightly offset from and inclined to each other.

30 Member 13, which may be termed the concentric member, is mounted concentrically of and for rotation with drive shaft 15, having its periphery 35 made up of a plurality of bar-like members 16. The concentric member 13 in the embodiment of Figures 3 and 4 may be fixed to the drive shaft 15 by means of a key and nut 17 which provides for easy removal of this member when desired. Drive 40 shaft 15 may be journaled in the correct position in frame member 18, on which eccentric member 14 may be rotatably mounted with its axis in offset and inclined relationship with regard to the 45 axis of member 13. The periphery of member 14 is composed of a plurality of longitudinally extending bars 19, the number of which is preferably the same as that of the bar-like members 16 of member 13 and which are alternately disposed with respect to said bar-like members 16.

50 These bars 19 may be supported in any suitable manner, as that shown, in which they are supported from one end by being clamped between the outer and inner ring-like members 21 and 22, respectively internally and externally tapered and secured together by screws 23. The inner ring-like member 22 may be provided with a central sleeve 24, concentric therewith, which is journaled on frame member 18 with its axis in the aforesaid offset and inclined relation to that of member 13. A tubular flexible sealing member 25, which may take the form of a bellows as shown, may be provided to enclose that portion of the mechanism surrounding shaft 15 between members 13 and 14, and thus provide protection 60 for this mechanism as well as prevent the escape of lubricants, etc.

65 Rotation of the drive shaft 15 causes concentric member 13 to rotate therewith and contact between the bar-like members 16 of member 13 70 and the bars 19 of member 14 causes the latter member to rotate. Rotation of the reel causes the thread to wind on the reel and, by the action of the offset and inclined members 13 and 14, to 75 form spaced substantially helical turns which

progress axially along the reel in a manner more fully described in the aforesaid Knebusch application. By suitable construction and rotation of the reel, the thread may be caused to wind on the reel at the rear and progress in substantially helical turns toward the front, or from left to right in Figure 3, where the thread is discharged or taken off, as by suitable guide means.

A reel of the open-ended type; that is, a reel supported at one end only with no projecting shaft at the other end, such, for example, as the reel described, offers certain advantages in threading up or manipulating the thread while starting it on the reel, as well as certain constructional advantages arising out of the possibility of supporting the reel at one end only. With a reel of this or similar type, any desired length of thread within reasonable limits may thus be continuously but temporarily stored in a relatively small space without tangling or interference of the thread. Thus it is possible in a relatively small space to perform various processing treatments on the thread, which operations would otherwise require much greater space and more complication of spinning machine construction than is practicable in the conventional evaporative spinning practice.

Figure 5 illustrates a modification of the type of reel illustrated in Figures 3 and 4, in which modification means are provided for supplying treating medium, either gaseous or liquid, to the thread or the like on the reel from the interior of the reel. In the case illustrated, the concentric reel member 13a has a hollow body or chamber 26, the inner end of which is closed off by the hub 27. The outer end thereof is closed off by cover or cap 28, held in place by a plug bolt 29 which also closes the end of the hollow shaft 15a and secures concentric reel member 13a in place against pin 30 on shaft 15a. Ports 31 in the hollow shaft 15a, by means of which the treating medium is supplied to the reel, communicate with the interior chamber 26 of the reel. A plurality of holes 32 in the wall of the chamber 26 permit the treating medium in the interior of the reel to reach the thread stored thereon. The mechanical operation of this reel may be exactly similar to that of the reel of Figures 3 and 4.

For convenience, the invention will be described in connection with thread-advancing reels of the type shown in Figures 3 and 4 and Figure 5, although other forms of thread-storage devices may be used instead.

In the embodiment of Figures 1 and 2, a reel of the type illustrated in Figure 5 is used, but it is apparent that by suitable modification of the apparatus the reel of Figures 3 and 4 may be employed. The reel may be mounted and positively driven in the manner shown. Reel frame member 18 is mounted on the frame 33 of the spinning machine. Each reel in the horizontal series formed by the reels in adjacent chambers may be driven from a longitudinal drive shaft 34 through helical gears 35, 36, the latter of which is mounted for rotation with the reel drive shaft 15a. Treating medium is supplied to the interior of the reel, from which it reaches the thread on the reel, from the supply pipe 37 which communicates with the hollow shaft 15a of the reel by any suitable means.

The reel 11 is shown disposed in a chamber 38 formed by the partition 39 and separated from the evaporative chamber 3. The treating medium supplied to the thread on the reel 11 may be exhausted from chamber 38 by the pipe 41.

Evaporative medium may be supplied to evaporative chamber 3 by a supply pipe 42 or from chamber 38, if an evaporative medium is supplied thereto. Heating pipes 43 may be provided in the evaporative chamber 3 to heat the evaporative medium. The solvent-laden evaporative medium may be drawn off by any suitable means, as through the exhaust manifold 44 which may be positioned at the top of the evaporative chamber 3. If a heated evaporative medium is used, the spinning solution may, if desired, be heated by causing it to pass, on its way to the spinneret, through a passage 40 which may be heated by the gases in the manifold, as shown.

It has been found that the filaments dry sufficiently at a short distance from the spinneret to retain their shape and eliminate sticking even though they still contain a large amount of solvent.

Therefore, the distance between the spinneret 20 and the reel succeeding it may be relatively short and thus make it possible to decrease the required height of the evaporative chamber. The remainder of the volatile solvent in the thread may be removed therefrom while the thread is compactly stored on one or more thread-storage devices. For example, in the embodiment of Figures 1 and 2, the thread 1 is solidified sufficiently in the short travel through evaporative chamber 3 to be capable of being wound on the reel 11 in the chamber 38. Since it has been found that a large proportion of the volatile solvent is removed in a short distance after the thread leaves the spinneret, much of the volatile solvent in this case is removed by evaporation in chamber 3. The remainder may be removed in chamber 38 while the thread is stored on the reel 11 therein by means of evaporative medium supplied to the thread, as from the interior of the reel.

By the employment of a suitable thread-storage device on which a very considerable length of thread is stored in a small space, it is possible to subject a much greater length of thread than heretofore possible to the action of an evaporative medium.

Thus, for example, with a reel of five inch diameter which has a thread-bearing surface five inches long, it is readily possible to store more than fifty feet of thread, meanwhile subjecting it to treating or evaporative medium, since fifty turns or more of thread may be easily stored on a reel of this size. Therefore, the possibility of complete removal, and consequent recovery, of the volatile solvent before the thread leaves the chamber is greatly increased, since the thread may be subjected to evaporative medium for a much longer period than heretofore possible. Also, a much smaller amount of evaporative medium is required, since the thread is subjected to it for a longer period of time. Likewise, by the use of the thread-storage device in chamber 38 separate from the evaporative chamber 3, it is possible to provide different evaporative conditions in the two chambers, which may result in certain advantages; for instance, it may be desirable to maintain temperature differences in the two cells in which case the luster and/or other physical properties of the thread may be controlled to a certain extent.

When the spinning machine is being started, the thread drops straight down from spinneret 2 as in conventional machines, as illustrated by the dotted lines 1' of Figure 2, through slot 45, and past guide 46, which associates the filaments, to the reel 11. Access to the reel may be had for

threading up purposes through the door 47. The thread is wound roughly a few times around the reel after which the action of the elements thereof during rotation causes the thread to form spaced substantial helical turns which progress axially along the reel until they are discharged or taken off at the end thereof. A guide 48 may be provided to guide the thread at this point. Means, such as the sliding latch 50, may be provided to reduce the opening at slot 45 after the thread has been started on reel 11. Thread may leave the chamber, as shown, at the bottom through a slot 49 which may be formed at the junction of the door 47 and the wall of the chamber 38. The thread may thereafter pass to the collecting device.

In conventional evaporative spinning practice, the thread is generally twisted immediately after being produced. Therefore, various forms of 20 twisting apparatus are shown in the embodiments of this invention as the collecting devices, although any suitable collecting devices may be used. Since a positively driven reel is used, the draw-off roll, employed on conventional machines 25 to draw the thread from the spinneret, may be dispensed with and the thread passed directly from the reel to the cap-twisting device 12, as through the guide 51 which may be pivotally mounted to be swung out of the way when the 30 cap 52 is removed from the twister. The employment of the reel and the elimination of the draw-off roll also makes it possible to place the cap-twisting apparatus under the evaporative chamber, as shown in Figures 1 and 2, or partly 35 under the chamber, as shown in Figures 10 and 11, in either of which cases a considerable saving of floor space results.

In the twisting apparatus shown, the rotatable whirls 53 of a pair of adjacent twisters are driven by belt 54 from the conventional drum 55, a suitable tensioning device 56 and guide roller 57 being provided for each belt. The spindle shafts 58 of all twisters may be mounted on the spindle rail 59 which is rigidly fastened to the frame of the spinning machine. The apparatus for vertically reciprocating the lifting rail 61 comprises one or more chains 62, each of which is fastened to a sprocket 63 rigidly mounted, as by a key, on the shaft 64 extending longitudinally of the machine. Shaft 64 is given an oscillatory motion 40 by means of a chain 65 fastened to sprocket 66 which is rigidly mounted on shaft 64, which chain 65 is given the required motion to cause it to wind and unwind from sprocket 66 by means of the lever 67 actuated by the cam 68 from shaft 50 69. Shaft 69 is given the desired rotating motion by some suitable means, not shown.

The spinning machine embodied in Figures 1 and 2 may be considerably shorter than conventional spinning machines. As shown, the spinneret 2 may be easily observed from the floor through the window 10 provided in the wall of the evaporative chamber 3. Door 71 may be provided, as in conventional machines, for access to the spinneret and candle filter 9 from the rear of the machine. To furnish easy access to the unsupported end of the reel 11, a similar door is preferably provided at the front of the machine.

The embodiment of Figures 6 and 7 embraces 70 a plurality, in this case two, of thread-storage devices which may be of the type illustrated in Figures 3 and 4 disposed in the evaporative chamber 3. The reels, bearing reference numerals 74 and 75, are, for the purposes of illustration, shown 75 positioned in a stepped arrangement, the axes

of the reels being horizontal, with the discharge end of the first reel adjacent the receiving end of the succeeding reel. The reels may be mounted and driven in any suitable manner. In that shown, the reel frame members 18 are supported by the longitudinally extending spinning machine frame members 16. Each reel may be driven through gears 35, 36 from one of the longitudinally extending drive shafts 34, each of which may drive all the reels in a horizontal series, and 10 each of which may be driven by suitable means, not shown. Evaporative medium, such as air, may be supplied to the evaporative chamber 3 by some means as pipe 17. Means for heating the evaporative medium in the chamber, as heating pipes 43, may be provided. The solvent-laden evaporative medium may, as in conventional machines, be drawn out of the evaporative chamber 3 at the top by means of the exhaust manifold 44.

The thread 1, which in the conventional manner is formed by extrusion of the spinning solution from the spinneret 2 into the evaporative chamber 3, passes through guide 19, which associates the filaments of the thread 1 and guides it on the first reel 14 on which the thread is continuously temporarily stored and advanced in substantially helical form axially of the reel 14 until it leaves the reel, passing through guide 81 to the receiving end of the next reel 15, where it is stored and advanced axially until caused to 30 leave the reel by guide 82. The thread 1 may leave the evaporative chamber 3 through the bottom as in the embodiments of Figures 1 and 2 or through a slot 83 in the side of the chamber, as shown. Doors 85, 86 may be provided for access to the reels for threading up, etc. Windows may be provided in the doors so the operation of the reels may be observed without opening evaporative chamber 3. The slot 83 through which the thread leaves the chamber may be located at the lower edge of door 86. As in the previous embodiments, a window 10 may be provided at the front or operating side of the apparatus for observance of the spinneret, etc., while the door 71 may be provided at the rear for access to the spinneret 2 and candle filter 9.

Certain advantages arise from using one or more thread-storage devices in an evaporative atmosphere. In the usual evaporative spinning, the surface of each filament, upon extrusion, hardens first, since it is exposed to a highly evaporative medium. A short distance away from the spinneret, the surface of the filament is hard enough so that stickiness is not present, but a plastic core is contained within the skin-like outer surface of the filament. In conventional evaporative spinning practice, the thread is passed through the evaporative chamber at a speed which makes uniform solidification of each filament throughout its cross section impossible 60 before it is withdrawn from the chamber. The skin-like outer surface, which has hardened rapidly, often breaks due to the shrinkage of the core when it hardens, with consequent impairment of appearance and physical properties of the thread. 65 By exposing the thread to the evaporative atmosphere while a relatively long length of thread is stored on one or more thread-storage devices, it is possible to obtain more uniform solidification throughout the cross section of each filament, 70 since such drastic evaporative conditions as are required to evaporate the solvent and solidify the thread in an extremely short time in ordinary practice are not required if a longer period for evaporation is allowed.

Thus in the embodiment of Figures 6 and 7, what is in effect a two-stage evaporation process is obtained by the use of the reels 74, 75. That is, evaporative medium at the level of reel 74 contains a certain amount of the volatile solvent due to evaporation of solvent from the thread stored on reel 75. The thread on reel 74, being stored for an interval in this evaporative atmosphere, has time for a more uniform degree of solidification to occur throughout, since the outer surface of the filaments will tend to become softer while the plastic core will solidify somewhat. A similar action takes place on the lower reel 75 except that the thread on this reel, being exposed to a fresh evaporative medium, as from pipe 71, will become uniformly substantially completely solidified, without checking or cracking of the surfaces of the filaments. Of course, if more than two reels are used, evaporative time is increased with an increase in beneficial results.

By enclosing the reels in suitable processing chambers, as in other embodiments illustrated, it is possible to apply evaporative media of different characteristics to the thread and thus obtain a measure of control over the evaporation heretofore impossible. In this embodiment, as in others in which an evaporative medium is applied to the thread while it is stored on a thread-storage device, an increase in the length of thread exposed to the evaporative medium without a corresponding increase in the length of the evaporative chamber is made possible. Much the same holds true of various other resulting advantages, such as a lower required temperature of the evaporative medium, since more time is allowed for evaporation; less required evaporative medium, since the thread is exposed to the evaporative medium for a longer period; accurate control of the characteristics of the evaporative medium, since a smaller quantity is used; consequent economies of operation, etc.

Another embodiment of the invention in which a plurality of thread-storage devices, which may take the form of reels of the types described, are associated with the evaporative chamber is illustrated in Figures 8 and 9. To illustrate another possible arrangement of the reels with regard to each other, the reels bearing reference numerals 87, 88, 89 are shown disposed in a stepped arrangement, in which the thread-receiving end of each reel except the first is adjacent the discharge end of the preceding reel, the axes of all reels being parallel and inclined from the horizontal. The reels may, if desired, be separated from the evaporative chamber 3 and from each other as by partitions 91, 92, 93, in which case chambers 94, 95, 96 enclosing the respective reels 87, 88, 89 are formed. Various treating media may therefore be applied to the thread stored on said reels. The reels may be of a type similar to the reel of Figure 5 in which the treating medium may be supplied to the thread from the interior of the reel.

Thus in the apparatus of Figures 8 and 9, the treating medium for each reel in a horizontal series is supplied from the pipe 37 to the hollow reel drive shaft journaled in reel frame member 18, which is so formed and mounted as to support the reel in the desired inclined position. Suitable means as pipe 41 may be provided for exhausting or removing the treating medium from the chamber enclosing each reel. The reels may be driven, if desired, by means similar to that previously illustrated which comprises a longitudinal drive shaft 34 for each horizontal series of reels from

which each reel in the series is driven by helical gears 35, 36. Doors 98, 99, 100 may be provided for access to the respective reels while guides 102 may be provided to guide the thread as it starts on each reel. A guide 103 is supplied for the thread 1 as it leaves the last chamber 96, as through slot 83 at the edge of door 100.

The evaporative chamber 3 may be relatively short, as in the previous embodiment, since, if desired, the remaining solvent in the thread 1 may be evaporated on one or more of the succeeding reels. Evaporative medium may be drawn into chamber 3 from one or more of the succeeding chambers enclosing the reels, if evaporative medium is supplied thereto, or the evaporative medium may be supplied by some independent means as pipe 42. Evaporative medium may be exhausted from evaporative chamber 3 in any desired manner as by the exhaust manifold 44. Heating means, as pipes 43, may be provided in the chamber. Window 70 in the wall at the front or operating side of the machine may be supplied for observing the spinneret and thread while the door 71 may be furnished in the opposite wall of the machine for access to the upper part of the evaporative chamber.

While all the previously described embodiments have included relatively short evaporative chambers, suitable thread-storage devices may, according to this invention, be advantageously employed in association with relatively long evaporative chambers, chambers as long, for instance, as those of conventional spinning machines. Thus, in the embodiment of Figures 10 and 11, the thread 1 after being formed by extrusion of the spinning solution into relatively long evaporative chamber 3 passes next to reel 105, on which various processing treatments may be performed, after which the thread passes to another reel 106 outside of the evaporative chamber, on which reel other processing treatments may be applied to the thread, after which it may pass to a suitable collecting device, as cap-twister 12.

As shown, the reel 105 is adapted for the application of liquid treating medium to the thread stored thereon. The liquid treating apparatus may take any suitable form, as that illustrated, which comprises a reagent distributor 107 positioned above the reel, from which the treating liquid is showered down on the thread on the reel and which is supplied from the reagent supply line 108 which may extend longitudinally of the spinning machine and thus be common to all reels in the horizontal series. The liquid, as it leaves the reel 105, may be deflected to the drain pipe 109 by means of a sloping partition 110. Drain pipe 109 may also extend longitudinally of the spinning machine and serve all reels in a horizontal series, and may communicate with the sewer if it is not desired to re-use the treating liquid or, in conjunction with the supply pipe 108, may communicate with recirculating and makeup systems.

A partition 112 may be provided to segregate the space surrounding the reel from the evaporative chamber 3 forming, in effect, a treating chamber 113. Reel 105 may be driven from a longitudinally extending drive shaft 34 through gears 35, 36. Door 110, which may contain a window, is shown as providing access to the chamber 113 and reel 105. A suitable means, such as sliding latch 114, may be provided to decrease the opening in the partition 112 through which the thread passes to the reel, after the thread has once been started on the reel. A guide 115, to

associate the filaments and guide the thread as it starts on the reel 105, and a guide 116 to guide the thread as it leaves the reel may be provided. A slot 83 at the lower edge of the door 110 is shown through which the thread leaves the chamber.

If a liquid treatment is applied to the thread, it may be desirable to dry the thread before it is collected. In the embodiment shown, the 10 thread may readily be dried on reel 106. The apparatus shown for drying comprises a housing 117 enclosing substantially all of the reel 106 which housing is supplied with gaseous drying medium, such as heated air, from conduit 120 15 which may supply all similar drying housings and which may be supplied with drying medium from a suitable source. For the purpose, among others, of providing ease in threading up the reel, the housing 117 may be formed with a hinged cover 20 118 or other suitable means for allowing access to the reel. The cover 118 may be swung back, as shown by the dotted lines 118', when threading up the reel and may be provided with a slot 119 at its edge to prevent interference with 25 the thread starting on the reel when the cover 118 is closed. Reel 106 is shown as being supported by means of bracket 121 fastened to the frame of the spinning machine and being driven by chain 122 on sprocket 123 on the reel drive 30 shaft 15, which chain 122 is driven by sprocket 124 on the drive shaft 125 which may serve all similar reels and is driven by suitable means not shown.

The reel 106 is shown in a position corresponding 35 to that of the draw-off roller in conventional evaporative spinning machine; that is, with its axis extending longitudinally of the machine, and may be employed in that capacity if there is no reel preceding it, with the added advantage over 40 the conventional draw-off roller that various processing treatments may be applied to the thread thereon. Obviously, the arrangements of the reels with regard to the evaporative chambers, as well as methods of mounting and driving 45 the reels 105 and 106 and the methods of applying treating mediums to the thread stored thereon, are susceptible of various modifications.

The collecting device is shown as cap-twister 12 to which the thread passes from reel 106 50 through guide 51, which may be pivoted as shown. Cap-twister 12 may be actuated by mechanism similar to that of Figures 1 and 2, wherefore no further description thereof is believed necessary. Other details of the apparatus may be conventional; for example, the means, such as pipe 42, 55 for introduction of the evaporative medium into evaporative chamber 3; heating means, such as pipes 43 in the evaporative chamber; exhaust means, such as manifold 44, for removing the solvent-containing evaporative medium from chamber 3; window 70 for observing the spinneret and run of the thread; and door 71 for access to the upper region of the evaporative chamber.

It may also be advantageous in conjunction 65 with relatively long evaporative chambers to perform certain processing operations solely by means of gaseous media. This may be accomplished by apparatus such as that of Figures 12 and 13 in which, for the purpose of illustration, 70 another possible arrangement of reels is shown. In this arrangement, the reels, of which two bearing reference numerals 126, 127 are shown in connection with each evaporative chamber 3, are disposed in what might be termed staggered relationship with their axes parallel to each other

and extending longitudinally of the spinning machine. The receiving end of the succeeding reel is adjacent the discharge end of the preceding reel. A convenient method of mounting and driving the reels is illustrated on a larger scale 5 in Figure 14. As can be seen from Figures 12, 13 and 14, corresponding reels in adjacent chambers may be disposed with their driving ends adjacent the wall between them, in consequence of which fact two reels may readily be driven 10 by the same power means.

If desired, the reels 126, 127 may be separated from the evaporative chamber 3 or from each other by partitions 128, 129, which provide processing chambers 131, 132, each of which may be 15 provided with treating medium supply and exhaust conduits 133, 134 and doors 135, 136 for access to the chambers and reels. Suitable means, such as a slide latch 137 shown on the partition 128 between the first reel 126 and the 20 evaporative chamber 3, may be provided to reduce the size of the aperture therein provided for the passage of the thread. As in certain previously described embodiments, the evaporative medium for evaporative chamber 3 may be supplied from one of the processing chambers 131, 132, if evaporative medium is used therein, or it may be supplied by some independent means, as pipe 42. Other details of the apparatus associated with the evaporative chamber may be more 30 or less conventional, such as spinneret 2, candle filter 9, heating pipes 43, exhaust manifold 44, window 70, door 71, etc.

Suitable means, such as guides 138, 139, may be supplied to guide the thread as it starts on 35 the last reel. As in the other embodiments, a guide 141 may be located adjacent the discharge end of the last reel 127 to guide the thread as it leaves the chamber 132, as by slot at the edge of door 136. A guide 51, which may, if desired, 40 be pivoted, may be provided for the thread as it passes to the collecting device, in this case cap-twister 12 which may be actuated by apparatus such as that previously described.

Figure 14 may be taken as representative of 45 the means of mounting and driving all of the reels. For convenience, the reel at the left of Figure 14 will be assigned reference numeral 127a and the one at the right 127b. In the embodiment shown, the boss member 18' on which the 50 eccentric member of each reel is mounted and in which is journaled the drive shaft for the reel, is supported on or formed integral with cap-like member 143. Both cap-like members 143 are fastened diametrically opposite on the wall 55 148 between adjacent chambers. On drive shaft 15b of one reel 127b is mounted for rotation sprocket 144, rotated by chain 145, which is driven by sprocket 146 mounted on drive shaft 147 which may extend longitudinally of the machine and drive all the reels in a horizontal series. The drive from the drive shaft 15b to drive shaft 15 of reel 127a may be accomplished by coupling member 149. Suitable collars 150 are shown fixed to shafts 15 and 15b to prevent end 60 play thereof and locate the reels axially. The reel mounting and driving means illustrated is simple and inexpensive of construction and may be quickly and easily assembled and disassembled. 70

Numerous advantages, in addition to the reduction in height of the spinning machine, increase in effectiveness in the removal of solvents from the thread or the like, etc., accrue from the employment of one or more thread- 75

storage devices in the manufacture by an evaporative method of thread or the like, regardless of its nature.

For instance, it is possible, according to this invention, to stretch or shrink the thread or the like while still plastic by suitable differences in the peripheral speeds of the thread-storage devices. A limited amount of stretching or shrinking may also be obtained by so constructing one or more of the thread-storage devices or reels that its diameter increases or decreases as the thread or the like progresses axially along it. Stretching of the thread or the like may also be secured by causing one or more of the reels to be rotated by the drag of the thread or the like as it is drawn off the reel since a thread-storage reel of this type also performs a thread-advancing function when operated in this manner. Suitable combinations of these methods may be used if desired. Stretching of the thread or the like while still plastic is often desirable since improved physical properties, such as increased tensile strength, etc., result.

It has been found that improved results are obtained when the skin-like outer surface, which first forms on the thread or the like immediately after extrusion, is softened as by means of suitable solvents, preferably the ones used in the spinning solution, applied in liquid or vapor form before or during the stretching of the thread or the like. The outer surface, being thus softened, does not crack or check as the thread or the like is stretched. It has also been found that thread or the like of cellulose acetate may be rendered resistant to the action of hot or boiling aqueous liquids by stretching it beyond its elastic limit after it is finally set, the operation being carried on, if desired, after the thread or the like has been treated with water or a suitable liquid or vaporous agent.

According to this invention, it is possible to apply such liquids or vapors to the thread or the like for these or other purposes before or during stretching. This can be done, for instance, with the aid of the apparatus of Figures 8 and 9 and of Figures 12 and 13, particularly in the application to the thread or the like of vaporous or gaseous treating mediums or solvents. It can be accomplished with the aid of the apparatus of Figures 10 and 11 in the application of liquid treating mediums or solvents. In each case, the thread or the like is appropriately stretched by suitable differences in the peripheral speeds of adjacent reels or by any of the other above-mentioned methods. The thread or the like is dried if desired after stretching, as by drying reel 106 of Figures 10 and 11.

It is known that for certain types of thread or the like, beneficial results are derived from evaporating the solvent in an atmosphere richly laden but not saturated with solvent vapors, rather than in an atmosphere very low in such vapors. The formation of the skin-like surface on the thread or the like is retarded or eliminated with elimination of the consequent cracking and checking of the surface which occurs when the plastic core of the thread or the like hardens. Other advantages also result, such as control over the shape of the cross-section, control over the luster, etc. Such a process may readily be performed according to this invention, as on apparatus comprising one or more thread-storage devices disposed in a processing chamber, since a much longer length of thread or the like than

heretofore possible may be subjected to such solvent laden evaporative atmosphere.

Recovery of all such solvents which in the ordinary practice of such a process is difficult, is facilitated by this invention since one or more succeeding chambers each containing one or more reels may be devoted, if desired, to the recovery of solvents which would otherwise be lost.

The luster of certain types of thread or the like produced according to evaporative spinning methods may be reduced or enhanced by the application of suitable gaseous, vaporous, or liquid treating media. Thus in the case of thread or the like of organic derivatives of cellulose; e. g., cellulose acetate, treating media such as steam, water, or liquids or vapors of such hydrocarbons as benzene, gasoline, or of certain alcohols, or of certain esters, ethers, etc. may be used to reduce the luster of the thread or the like. Similarly, xylene may be mentioned as an example of an agent for enhancing the luster of the thread or the like. Such processing treatments may be easily performed according to this invention since they may be applied to the thread or the like on one or more thread-storage devices.

It is often desirable to subject the thread or the like to different evaporative conditions at different stages of evaporation of the solvent from the thread or the like, in which case certain physical properties of the thread or the like result. This may easily be accomplished according to the invention, since the thread or the like may be subjected to different evaporative conditions while stored on different thread-storage devices. It has been found heretofore that a temperature in the vicinity of the spinning nozzle different from that of the evaporative medium in other portions of the evaporative chamber often produces desirable results.

As an example, it has been found that if thread or the like is spun into a relatively cold evaporative atmosphere and subsequently subjected to heated evaporative medium, beneficial results with regard to uniformity, tensile strength, control over the luster, etc., of the thread or the like are obtained, presumably because the solvent is withdrawn from the thread or the like only gradually at first, preventing the formation of a skin-like outer surface. However, attempts to produce the thread or the like according to such process have hitherto met with little success because of the much longer travel through the cold evaporative medium required of the thread or the like, since the solvent is extracted much more slowly in a cold evaporative medium than in a heated medium.

According to this invention, however, thread or the like may be produced under such conditions without difficulty, since it is possible to spin the thread or the like into a relatively cold evaporative chamber in which a portion of the solvent is extracted and thereafter extract the remainder of the solvent, after the thread or the like has hardened sufficiently to prevent stickiness, in one or more relatively small evaporative chambers in which the evaporative atmosphere may or may not be heated, and in which the thread or the like is stored on one or more thread-storage devices. Thus, for instance, apparatus similar to that of Figures 12 and 13 may be used. The disadvantages previously encountered because of the excessive space and size of the machines required are therefore eliminated by this invention.

Various other liquids, gaseous, or vaporous proc-

essing treatments may be applied to the thread or the like by means of this invention; for instance, it may be found desirable to dye or tint the thread or the like with some distinctive color, or, as, for example, for the purpose of identification during subsequent manufacturing operations. Such color may, if desired, be of a character to facilitate its subsequent removal by some simple operation, such as washing with water, after it has served its purpose, as after the thread or the like has been formed into a fabric. Such tinting or other dyeing of the thread or the like may, according to this invention, be applied to the thread or the like continuously with its production by suitable apparatus, such as the liquid processing apparatus associated with reel 105 of the embodiment of Figures 10 and 11, after which the thread or the like may be dried, as on reel 106, before being collected.

In all processing operations, such as those above, the invention provides uniformity of treatment, as desired; ease of control of the treatments; economy of treating medium; economy of space, as well as other advantages.

Non-uniform or novelty effects may also be readily produced on the thread or the like by the methods and apparatus of this invention. Thus the peripheral speeds of the thread-storage devices with respect to each other and/or with respect to the speed of extrusion of the spinning solution from the spinning nozzle may be varied during the operation of the apparatus at regular or irregular intervals, in which case varied stretching or shrinking effects are applied to the thread. Likewise, suitable liquids or vapors, such as solvent liquids or vapors, may be applied at regular or irregular intervals to the thread or the like when it is stored on one or more thread-storage devices, in which case the luster and/or surface characteristics of the thread or the like will be correspondingly affected; etc.

The invention is particularly advantageous in the manufacture of thick filament bundles intended for use in making staple fiber, such articles being of relatively high denier. Such products are ordinarily difficult to produce according to the conventional down-spinning evaporative methods because the filament bundle, being very soft immediately after issuing from the spinning nozzle, is not strong enough to support the weight of the length of the previously formed product extending downward into the evaporative chamber. Other difficulties arise from the fact that a substantially longer travel is required through the evaporative medium since more time is required to withdraw the solvent from articles of large denier than from articles of small denier, requiring, in conventional practice, either slower speeds of production, longer evaporative chambers, or more drastic evaporative conditions, all of which are disadvantageous.

For these reasons, it is advantageous to manufacture such articles of large denier according to the present invention. The greater part of the freshly spun product may be supported in close proximity to the spinning nozzle on one or more thread-storage devices, thus eliminating the difficulty arising from its relatively great weight. Similarly, a much longer length of the product than heretofore possible may, by storing it on one or more thread-storage devices, be subjected to the action of the evaporative medium, the former difficulties of slow speed of production, excess of machine height due to the length of the evapo-

tive chamber heretofore required, etc., are therefore eliminated.

Heretofore one of the factors limiting the speed of manufacture of thread or the like by an evaporative spinning method has been the necessity for allowing a sufficient time for hardening of the thread or the like and removal of the solvent. Increase in speed of production would, according to conventional practice, necessitate a much longer evaporative chamber to allow a sufficient period for evaporation of the solvent; otherwise, an even larger loss of residual solvent contained in the thread withdrawn from the chamber would result due to insufficient evaporation. According to this invention, however, a much longer length of thread or the like than heretofore possible may be subjected to the action of the evaporative medium in a small space, thus permitting complete extraction of the solvent from the thread or the like. Thus great increases in speeds of production of the thread or the like are possible without increases in space requirements or losses of solvents.

Only a few of many possible embodiments of the invention have been shown and described; indeed, various other embodiments of the invention may be devised and numerous modifications may be made in the embodiments herein shown without departing in any way from the spirit of the invention. It is obvious, for instance, that the arrangements of thread-storage devices shown herein as employed in or in connection with relatively long evaporative chambers may be employed in or in connection with relatively short evaporative chambers and vice versa. Similarly, although the invention has been described in connection with down-spinning evaporative processes, it may also be employed advantageously in connection with up-spinning evaporative processes. As has been pointed out, the invention transcends the manufacture of multiple filament artificial silk thread of cellulose acetate, being applicable to any thread or the like capable of being manufactured by an evaporative spinning method.

The invention is not restricted to the particular type of thread-storage device hereinabove shown and described. Any suitable type of thread-storage device may be used, but preferably one on which, by the action of the device, thread or the like is continuously but temporarily stored in a relatively large number of helical or generally helical turns. Whereas the thread-storage device hereinabove described comprises two generally cylindrical cage members mounted with their axes slightly offset from and inclined to each other, a similar effect may be obtained by means of two generally cylindrical members mounted with their axes similarly inclined but offset sufficiently to separate the peripheries of the two cylindrical members completely. The term "generally helical" as employed in the appended claims is intended to include this type of thread-storage device.

Other arrangements of the thread-storage devices, both with respect to each other and with respect to the evaporative chamber, may also be used, the arrangements of devices in the hereinabove described embodiments of the invention being merely illustrative. Likewise, the arrangements of the thread-storage devices of the various embodiments may, if desired, be interchanged. It is obvious that the partitions shown in certain embodiments of the invention as separating the thread-storage devices from each other and/

or from the evaporative chamber may be omitted under suitable conditions of operation; also, that more than one thread-storage device may be used, if desired, in each of the processing or evaporative chambers, as the case may be. It is also possible to have one or more thread-storage devices positioned outside of the evaporative chamber and to perform various desired liquid or gaseous processing treatments thereon in the 10 manner previously described.

It is intended that the patent shall cover, by suitable expression in the appended claims, whatever features of patentable novelty reside in the invention.

15 15. What is claimed is:

1. Apparatus for the manufacture of thread or the like by an evaporative spinning process comprising means for forming the thread or the like; a chamber for extracting solvent from the thread or the like to solidify the same; one or more thread-advancing thread-storage devices disposed in said chamber, each of said thread-advancing, thread-storage devices being constructed and arranged to positively advance the thread or the like in the general form of a helix characterized by a large number of turns; and means for subjecting the thread or the like on at least one thread-advancing, thread-storage device to processing treatment other than removal of the solvent from the thread or the like.

2. Apparatus for the manufacture of thread or the like by an evaporative spinning process comprising means for forming the thread or the like; an evaporative chamber; a plurality of thread-storage devices associated with said evaporative chamber on which the thread or the like is positively advanced in generally helical form, at least one of said thread-storage devices being disposed in said evaporative chamber; and means 40 for operating one of said thread-storage devices at a peripheral speed different from that of another of said thread-storage devices.

3. Apparatus for the manufacture of thread or the like by an evaporative spinning process comprising a first chamber; means in said first chamber for forming the thread or the like; a second chamber to which the thread or the like proceeds from said first chamber; and, disposed in said second chamber, at least one thread-storage device by means of which the thread or the like is continuously stored in the general form of a helix characterized by a large number of turns.

4. Apparatus for the manufacture of thread or the like by an evaporative spinning process comprising means for forming the thread or the like; a chamber for extracting solvent from the thread or the like to solidify the same; and, disposed in said chamber, a plurality of thread-advancing thread-storage devices each of which is constructed and arranged to positively advance the thread or the like in generally helical form, the receiving end of each thread-advancing, thread-storage device other than the first being disposed in opposite relation to the discharge end of the preceding thread-advancing, thread-storage device.

5. Apparatus for the manufacture of thread or the like by an evaporative spinning process comprising means for forming the thread or the like; an evaporative chamber; a thread-storage device disposed in said evaporative chamber by means of which the thread or the like is continuously stored in a large number of generally helical turns; and means for applying a treat-

ing medium to the thread or the like from the interior of said thread-storage device.

6. Apparatus for the manufacture of thread or the like by an evaporative spinning process comprising an evaporative chamber; means for forming the thread or the like disposed in said evaporative chamber; a thread-storage device by means of which the thread or the like is continuously stored in a large number of generally helical turns disposed in said chamber at a point 10 spaced from said thread-forming means by an amount sufficient to permit the thread or the like leaving said thread-forming means to achieve a condition of partial solidification before it reaches said thread-storage device; and, associated with said chamber, means for collecting the thread or the like.

7. Apparatus for the manufacture of thread or the like by an evaporative spinning method comprising an evaporative chamber; means for forming the thread or the like disposed in said evaporative chamber; a thread-storage, thread-advancing device of cantilever form disposed in said evaporative chamber at a point spaced from said thread forming means; a door in said evaporative chamber opposite the unsupported end 20 of said thread-advancing, thread-storage device from which door access may be had to said thread-advancing, thread-storage device; and means for collecting the thread or the like after 25 it leaves said evaporative chamber.

8. Apparatus for the manufacture of thread or the like by an evaporative spinning method comprising a vertically extending evaporative chamber; means for forming the thread or the like disposed in said evaporative chamber at the upper portion thereof; a unitary, thread-advancing reel associated with said evaporative chamber at the lower portion of said chamber whereby the thread or the like is withdrawn from said 40 thread-forming means; and means for collecting the thread or the like.

9. Apparatus of the character described in claim 8 in which means for subjecting the thread or the like to processing treatment are associated 45 with said reel.

10. Apparatus for the manufacture of thread or the like by an evaporative spinning process comprising means for forming the thread or the like; a chamber for extracting solvent from the thread or the like to solidify the same; one or more thread-advancing reels of cantilever form disposed in said chamber below said thread-forming means, each of said reels being adapted to receive the thread or the like at its supported 55 end and positively advance it toward its unsupported end in a large number of generally helical turns; and means for withdrawing the thread or the like from said chamber.

11. Apparatus for the manufacture of thread or the like by an evaporative spinning process comprising a chamber for extracting solvent from the thread or the like to solidify the same; means for forming the thread or the like disposed in said chamber; one or more thread-advancing reels of cantilever form disposed in said chamber, each of said reels being adapted to receive the thread or like at its supported end and positively advance it toward its unsupported end in a large number of generally helical turns; and means for withdrawing the thread or the like 65 from said chamber.

12. Apparatus for manufacturing thread or the like by a spinning method comprising an evaporative chamber for extracting solvent from the 70

- thread or the like to solidify the same; means for forming the thread or the like disposed in said chamber at one end thereof; a thread-storage device by means of which the thread or the like is 5 positively advanced in a large number of generally helical turns, said thread-storage device being disposed in said chamber at a point spaced from said thread-forming means by an amount sufficient to permit the thread or the like leaving 10 said thread-forming means to achieve a condition of partial solidification before it reaches said thread-storage device; and means for withdrawing the thread or the like from said chamber.
13. A method of manufacturing thread or the like by an evaporative spinning process comprising 15 the steps of forming the thread or the like; positively advancing the thread or the like, prior to complete solidification thereof, in a large number of generally helical turns in an evaporative chamber; positively advancing the thread or the like 20 in a large number of generally helical turns under conditions different from those obtaining in said evaporative chamber; and collecting the thread or the like.
14. A method of manufacturing thread or the like by an evaporative spinning process comprising the steps of forming the thread or the like; passing the thread or the like, prior to complete 25 solidification thereof, through an evaporative chamber; positively advancing the thread or the like 30 in a large number of generally helical turns under conditions different from those obtaining in said evaporative chamber; and collecting the thread or the like.
15. A method of manufacturing thread or the like by an evaporative spinning process comprising the steps of forming the thread or the like; passing the thread or the like, prior to complete 35 solidification thereof, through an evaporative chamber, meanwhile positively advancing the thread or the like within said evaporative chamber in a large number of generally helical turns; and collecting the thread or the like.
16. Apparatus for the manufacture of thread or the like by an evaporative spinning process 40 comprising a chamber for extracting solvent from the thread or the like to solidify the same; a spinning nozzle disposed in said chamber; and, spaced from said spinning nozzle, one or more 45 thread-advancing, thread-storage devices, each of said thread-advancing, thread-storage devices being constructed and arranged to positively advance the thread or the like in the general form of a helix characterized by a large number of 50 turns.
17. In the manufacture of thread or the like by an evaporative spinning process pursuant to which a volatile organic solvent is evaporated from a dispersion of a thread-forming mass in such volatile organic solvent, the steps of forming the thread or the like; evaporating the volatile organic solvent from the thread or the like while continuously positively advancing a relatively long length thereof in a large number of closely spaced generally helical turns in a zone 5 10 characterized by an evaporative medium secluded from the atmosphere; and passing the thread or the like out of the zone in which it is exposed to the action of said evaporative medium.
18. In the manufacture of thread or the like by an evaporative spinning process pursuant to which a volatile organic solvent is evaporated from a dispersion of a thread-forming mass in such volatile organic solvent, the steps of forming the thread or the like evaporating substantially all of the volatile organic solvent from the thread or the like by means of a gaseous evaporative medium while continuously positively advancing a relatively long length of the thread or the like in a traveling helix made up of a large number of closely spaced turns located in a closed chamber through which said gaseous evaporative medium is passed; and, after the thread or the like has been advanced in said 20 traveling helix, withdrawing the thread or the like from said chamber.
19. Apparatus for the manufacture of thread or the like by an evaporative spinning process comprising means for forming the thread or the like; a chamber containing an evaporative medium for extracting solvent from the thread or the like to solidify the same, said chamber having an opening therein through which the thread or the like may leave said chamber; and a self-threading, thread-advancing reel of cantilever construction disposed in said chamber at a point sufficiently spaced from said thread-forming means to permit the thread or the like to achieve a condition of at least partial solidification before it reaches said reel, said reel receiving the thread or the like at the supported end thereof, positively advancing it toward the unsupported end thereof in a large number of closely spaced generally helical turns, and discharging it adjacent the opening in said chamber.

FRED J. SAMERDYKE.
LOUIS E. LOVETT.

CERTIFICATE OF CORRECTION.

Patent No. 2,217,707.

October 15, 1940.

FRED J. SAMERDYKE, ET AL.

It is hereby certified that error appears in the printed specification of the above numbered patent requiring correction as follows: Page 1, first column, line 45, and second column, line 28, the words "The foregoing" and "Analogous" respectively, should mark the beginning of a new paragraph; page 9, first column, line 21, claim 1, after "thread-advancing" insert a comma; line 60, claim 4, after the syllable "vancing" insert a comma; line 65, same claim, for "opposite" read --apposite--; and second column, line 37, claim 8, strike out the comma after "unitary"; page 10, second column, line 21, claim 18, after "like" insert a semicolon; and that the said Letters Patent should be read with this correction therein that the same may conform to the record of the case in the Patent Office.

Signed and sealed this 21st day of January, A. D. 1941.

(Seal)

Henry Van Arsdale,
Acting Commissioner of Patents.
